LEVELING MACHINE

Fred L. Mooney, Lynn, Mass., assignor to United
Shoe Machinery Corporation, Flemington, N. J.,
a corporation of New Jersey

Application July 16, 1947, Serial No. 761,181

5 Claims. (Cl. 12—34)

1

This invention relates to machines for operating on shoes and more particularly to machines for shaping or leveling the bottoms of shoes. The invention is herein illustrated with reference to a fluid-pressure-operated leveling machine of the type illustrated in Letters Patent of the United States No. 2,230,244, granted February 4, 1941, in the names of Fred V. Hart and John J. Austin.

Machines of the type illustrated in the aforementioned patent are provided with a leveling roll which is held by springs, during the leveling operation, in engagement with the bottom of a shoe carried by a support mounted for swinging movements in directions lengthwise of the shoe thereon. Fluid-pressure-operated mechanism under the control of the operator is provided for imparting swinging movements to the shoe support during the leveling operation and for imparting tipping movements to the leveling roll. A fluid-pressure-operated motor is also provided for lifting the leveling roll against the action of the springs whenever desired during the leveling operation.

With the machine at rest and the shoe support located forwardly of the leveling roll to permit removal of a shoe from the support or positioning of a shoe thereon, the roll is held by the springs below the position it normally assumes during the leveling operation. To prevent stubbing the toe of the shoe when the support is initially moved rearwardly at the beginning of a leveling operation, the roll is lifted by the aforementioned fluid-pressure motor against the action of the springs. This motor is controlled by a valve which is positioned to direct pressure fluid to the motor when the support is in its forward position. Fluid is delivered by a pump under the control of a pressure-regulating valve which is automatically positioned with the support of its forward position to by-pass pressure fluid to a fluid reservoir. This pressure-regulating valve is operated upon straightening a pair of toggle links to shut off the by-pass so that the pressure of the fluid delivered to the various motors is high enough to operate the various mechanisms.

Upon rearward movement of the shoe support from its forward position a rod controlled thereby is moved forwardly and this forward movement of the rod is utilized to straighten the toggle links operating the pressure-regulating valve whereupon fluid under pressure is delivered to the roll-lifting motor and the roll is lifted to permit movement of the toe end of the shoe thereunder. Upon further movement of the support the valve controlling the roll-lifting motor operates to shut off

2

the flow of pressure fluid to the motor subjecting the roll again to the action of the springs which press the roll against the shoe bottom.

This mechanism heretofore employed for lifting the roll at the beginning of a leveling operation is satisfactory providing that the operator does not move the shoe support rearwardly too fast. If, however, the support is moved rearwardly sufficiently fast, the toe end of the shoe may move into operative relation to the roll before the pressure has an opportunity to build up in the system and lift the roll. Consequently some operators, in attempting to attain a high rate of production with the machine, may experience difficulties by stubbing the toe end of the shoe against the leveling roll. An object of the present invention is to overcome this difficulty by providing mechanism for very rapidly rendering the roll-lifting means operative in response to the initial rearward movement of the shoe support so that regardless of the rate of rearward movement of the support the roll will be lifted against the action of the springs before the toe end of the shoe moves thereunder.

This is accomplished in accordance with a feature of the invention by urging a control member for the roll-lifting mechanism into pressure-applying position by a spring and providing a latch for holding the member in a position in which it is ineffective to operate the roll-lifting mechanism, against the action of the spring with the support in its forward position. This latch is immediately released upon the initial rearward movement of the shoe support thereby minimizing the delay in operating the roll-lifting mechanism. During the forward movement of the shoe support at the conclusion of the leveling operation mechanism controlled thereby moves the control member back into its ineffective position after which the latch becomes operative to hold it in that position.

The above and other features of the invention, including various novel combinations of parts and details of construction, will now be described by reference to the accompanying drawings and pointed out in the claims.

In the drawings:

Fig. 1 is a view in right-hand side elevation of a machine in which the invention is embodied, parts of the structure being broken away and other parts being shown in section;

Fig. 2 is a side elevation on a large scale of the mechanism for operating the pressure-regulating valve, the parts being shown in the positions as

sumed when the shoe support is in its forward position;

Fig. 3 is a view similar to Fig. 2 showing the parts in the positions assumed at the beginning of the rearward movement of the shoe support, and

Fig. 4 is a view illustrating the positions of some of the parts illustrated in Figs. 2 and 3 during the leveling operation.

As shown in Fig. 1, the machine includes a shoe support or jack 10 pivoted on a shaft 12 for movements lengthwise of a shoe on the support to carry the shoe rearwardly and forwardly beneath a leveling roll 14. The leveling roll is mounted for turning movement on a rod 16 mounted in a holder 18 which is pivotally connected at 20 to a carrier 22. This carrier is mounted for tipping movements laterally of the machine about the axis of a forwardly and rearwardly extending shaft 24 supported in bearings at the top of the machine.

The holder 18 has a rearwardly extending arm 26 connected by a short link 28 to the rearwardly extending arm 30 of a bell crank lever 32 fulcrumed at 34 to the carrier 22. The bell crank lever has downwardly extending arms 36 carrying trunnions 38 extending into a circumferential groove 40 formed in a bushing 42 slidably mounted on the shaft 24. Pivotally mounted on a laterally extending shaft 44 supported by suitable bearings in the frame of the machine is an upwardly extending arm 46 the upper portion of which carries trunnions 48 extending into a circumferential groove 50 in the bushing 42. Mounted on the shaft 44 is a downwardly extending yoke 51 to which is connected, by a threaded rod 52, a yoke-shaped member 54 in which is pivoted a lever 56. This lever has oppositely extending arms of equal lengths to the ends of which are connected compression springs 58, 60 the latter bearing against an abutment 62 pivoted at 64 to the frame of the machine. The spring 58 at its upper end engages an abutment 66 pivotally connected to an arm 70 integral with the arm 46. These springs act to rock the arm 46 in a clockwise direction, moving the bushing 42 rearwardly along the shaft 24 and urging the roll 14 downwardly to exert leveling pressure against the shoe bottom. With the shoe support in its forward position, these springs hold the roll in a position below that which it normally assumes in the leveling operation, as shown in Fig. 1.

In order to prevent stubbing the toe of the shoe when the shoe support is moved rearwardly to carry the toe end of the shoe beneath the leveling roll, provision is made for lifting the roll against the action of the springs 58 and 60. Integral with the arm 46 is an arm 72 connected by an adjustable link 74 to one end of a lever 76 pivoted intermediate its ends on a pin 78 and its opposite end carrying trunnions 80 extending into a peripheral groove formed in the upper end of a plunger 82. This plunger projects upwardly from a piston movable vertically in a cylinder 84 as shown in detail in Patent No. 2,230,244, referred to above. Upon the introduction of pressure fluid into the lower end of the cylinder 84 the lever 76 is rocked in a counterclockwise direction causing the leveling roll 14 to be lifted against the action of the springs 58 and 60.

Introduction of pressure fluid into the cylinder 84 is controlled by a valve 86 the lower end of which is connected by a pipe 88 with a pressure-regulating valve 90 arranged upon downward movement of a plunger 92 to direct fluid under

pressure to the valve 86 from which it may be delivered to the cylinder 84 when the valve 86 is properly positioned. The constructions of the valves 86 and 90 are illustrated in detail in the aforementioned patent to which reference may be made for a detailed description thereof, although it is to be understood that in so far as the present invention is concerned the valves need not be constructed precisely as shown in that patent. It is sufficient to state here that when the plunger 92 of the pressure-regulating valve 90 is in the position illustrated in Fig. 1 the discharge side of the pump, by which pressure fluid is delivered to the various parts of the machine, is by-passed to the fluid reservoir but when the plunger 92 is depressed this by-pass is cut off and fluid at sufficiently high pressure to operate the various instrumentalities of the machine is delivered by the pump. The valve 86 has a stem 94 which, when in its upper position as shown in Fig. 1, delivers pressure fluid from the valve 90 to the cylinder 84 but when the stem is depressed the flow of pressure fluid to the cylinder 84 is cut off and the cylinder is allowed to exhaust. Thus it will be understood that as soon as the plunger 92 is depressed at the beginning of a leveling operation, in a manner to be described, pressure fluid flows into the valve 86 and thence to the cylinder 84 to lift the leveling roll against the action of the springs 58 and 60. Subsequently the stem 94 of the valve 86 is depressed to exhaust the cylinder 84 so that the leveling roll is forced downwardly into engagement with the shoe bottom by the springs 58 and 60. Thus it will be seen that the initial lifting of the leveling roll is dependent only upon downward movement of the plunger 92 to operate the pressure-regulating valve 90.

To the upper end of the plunger 92 is connected a link 96, the upper end of which is pivoted to the lower end of a depending arm 98 of a bell crank lever 100 secured to a rockshaft 102 shown mostly clearly in Fig. 2. The link 96 and the arm 98 of the bell crank lever form a toggle which is straightened upon clockwise movement of the bell crank lever thereby to move the plunger 92 downwardly, operating the pressure-regulating valve to supply pressure fluid to the cylinder 84 as well as to the fluid pressure motors for operating the jack and tipping the leveling roll, as described in the aforementioned patent. The toggle 96, 98 is arranged to be straightened at the beginning of the rearward movement of the shoe support so that no matter how fast the shoe support is moved to carry the shoe beneath the leveling roll the pressure-regulating valve will be operated early enough to insure admission of pressure fluid into the cylinder 84 to lift the leveling roll and prevent stubbing of the toe.

The bell crank lever 100 has a rearwardly extending arm 104 (Fig. 2) to the rearward end of which is connected a spring 106 by means of an eyebolt 108 passing through a pin 110 in the rearward end of the arm 104. The lower end of the spring is connected to a bracket 112 secured to the upper end of the casing of the pressure-regulating valve 90, the action of the spring being to move the bell crank lever 100 in a clockwise direction causing straightening of the toggle 96, 98. The toggle is locked in broken position, as shown in Figs. 1 and 2, when the shoe support is in forwardmost position, thereby to relieve the load on the pump. For thus locking the toggle in its broken position an arm 114 is secured to the shaft 102 and carries a pin 118 engageable with a latch 120 pivoted on a bracket 121 secured to

a rod 122 mounted for sliding movement forwardly and rearwardly of the machine.

The latch 120 is held in locking engagement with the pin 118 in the arm 114 to maintain the toggle broken and the valve plunger 92 in its upper position, with the shoe support in loading position, by a spring 124 secured to a depending portion of the latch 120 and to the bracket 121. At the beginning of the rearward movement of the shoe support the rod 122 is moved forwardly, as will be explained, and this initial forward movement operates to free the latch 120 from locking engagement with the pin 118. For this purpose a latch release arm 126 is journaled on the shaft 102 and extends rearwardly resting against a shoulder 128 on the upper portion of the latch. A spring 130, connected between an upwardly extending ear 132 on the arm 126 and a bracket 134 carried by the machine frame, holds the rearward end of the arm 126 against the upper surface of the latch. As soon as the rod 122 is moved forwardly the latch is caused to pivot by its engagement with the arm 126 in a clockwise direction against the force of the spring 124 lifting the forward end of the latch out of engagement with the pin 118 as shown in Fig. 3, whereupon the spring 106 snaps the toggle into straightened position moving the plunger 92 of the valve 90 downwardly. The arms 96, 98 of the toggle are prevented from moving beyond the straightened position by coacting shoulders 136 formed thereon as shown in Fig. 3.

The forward end of the rod 122 is pivoted at 138 (Fig. 1) to an arm 140 secured to a rockshaft 142 carried by the frame of the machine. Also secured to the rockshaft 142 is an upwardly extending arm 144 carrying at its upper end a roll 146 engageable with a downwardly extending arm 148 carried by the shoe support 10. The rod 122 carries a locknut 150 forming an abutment for one end of a coil spring 152 surrounding the rod, the other end acting against a fixed stop 154 on the machine frame. The spring 152 urges the rod 122 forwardly holding the roll 146 at the upper end of the arm 144 in engagement with the arm 148 carried by the shoe support. Upon rearward movement of the shoe support to carry the shoe into operative relation to the leveling roll the arm 148 moves forwardly whereupon the spring 152 causes forward movement of the rod 122 which releases the latch 120 (Fig. 3) and the toggle is immediately straightened by the spring 106. This causes the leveling roll to be moved upwardly against the action of the springs 58, 60 to permit the shoe to pass under the leveling roll without stubbing the toe. Upon further rearward movement of the shoe support the rod 122 moves forwardly to carry the latch 120 into the position shown in Fig. 4. The extent of forward movement of the rod 122 under the action of the spring 152 is limited by an arm 156 (Fig. 1) secured to the shaft 142. This arm carries a pin 158 movable in a slot 160 in the upper end of a bar 162 secured to a treadle 164 pivoted at 166 to the base of the machine. The treadle is normally held in the position shown in Fig. 1 by a spring 168 the upper position of the treadle being determined by a stop screw 170. When the pin 158 in the arm 156 reaches the upper end of the slot 160 the forward movement of the rod 122 is stopped and movement of the shoe support forwardly and rearwardly will have no effect on the rod until the support is moved forwardly enough to bring the extreme toe end of the shoe below the leveling roll.

At a predetermined point in the forward movement of the rod 122 during movement of the shoe support to carry the shoe beneath the leveling roll the valve 86 is operated to cut off the flow of fluid into the cylinder 84 and to exhaust fluid therefrom so that the roll is forced by spring pressure into engagement with the shoe bottom. This operation of the valve 86 is effected by a lever 172 connected by links 174 to the valve plunger 94. The lever is pivotally carried by a pin 176 and has an upwardly extending arm 178 carrying an eye bolt 180 to which is connected one end of a spring 182 the other end being connected to a pin 184 carried by the frame of the machine. The spring 182 acts to swing the lever 172 in a direction to move the valve stem 94 upwardly. The rod 122 carries an abutment 186 which acts on a downwardly extending arm 190 of the lever 172 to move the lever in a clockwise direction against the action of the spring 182 at a predetermined point in the forward movement of the rod. The abutment 186 is adjusted lengthwise of the rod so that it will act to move the lever 172 at the time that the toe end of the shoe moves under the roll 14 so that the roll is moved by spring pressure against the shoe bottom. At any time during the leveling operation, the operator, by stepping on the treadle 164, can impart rearward movement to the rod 122 sufficient to operate the valve 86 and lift the roll.

At the conclusion of the leveling operation the shoe support is again moved back to its original position as explained fully in the aforementioned patent causing the rod 122 to move from the position shown in Fig. 4 back to the position shown in Fig. 2. At the beginning of this rearward movement the valve 86 is operated to lift the leveling roll and then the latch 120 moves the arm 114 in a counterclockwise direction which causes similar movement of the bell crank lever 100, thus breaking the toggle. When the shoe support reaches its original or loading position the shoulder 128 of the latch 120 again engages the forward end of the arm 126, as shown in Fig. 2 thereby locking the latch in operative position with respect to the pin 118.

From the above it will be seen that upon very slight forward movement of the rod 122 the latch 120 holding the toggle in broken position is released whereupon the toggle straightens under the action of the spring 106 operating the pressure-regulating valve to apply pressure to the roll lifting mechanism, thus insuring that the roll will be lifted above the position it normally assumes during the leveling operation before the toe end of the shoe passes thereunder. By causing this rapid actuation of the pressure-regulating valve the danger that the pressure will not be built up sufficiently to lift the roll, in the event that the operator moves the jack rearwardly very fast, is substantially eliminated. Thus he is able to operate the machine at somewhat higher speed than was heretofore possible thereby obtaining higher production therefrom, while substantially reducing the danger of damaging the work.

Having thus described the invention, what I claim as new and desire to secure by Letters Patent of the United States is:

1. In a leveling machine, a shoe support, a leveling tool, means mounting said support for movement in directions lengthwise of a shoe thereon to cause the leveling tool to operate progressively along the shoe bottom, spring means for pressing the leveling tool upon the bottom of the shoe, mechanism for lifting said tool against the action

of said spring means, latch means rendering said mechanism ineffective with the shoe support in its forwardmost position in which a shoe carried thereon is located forwardly of the leveling tool, means operative upon release of said latch means for rendering said mechanism immediately effective, and means operative in response to the initial rearward movement of said shoe support for releasing said latch means.

2. In a leveling machine, a shoe support, a leveling tool, means mounting said support for movement in directions lengthwise of a shoe thereon to cause the leveling tool to operate progressively along the shoe bottom, spring means for pressing the leveling tool upon the bottom of the shoe, mechanism for lifting said tool against the action of said spring means, latch means rendering said mechanism ineffective with the shoe support in its forwardmost position in which a shoe carried thereon is located forwardly of the leveling tool, means operative upon release of said latch means for rendering said mechanism immediately effective, means operative in response to the initial rearward movement of said shoe support for releasing said latch means, and means operative in response to further rearward movement of the shoe support to carry the shoe beneath the leveling tool for rendering said mechanism ineffective whereupon the tool is held by the spring means against the shoe bottom during the leveling operation.

3. In a leveling machine, a shoe support, a leveling tool, means mounting said shoe support for movement in directions lengthwise of a shoe on the support to cause the leveling tool to operate progressively along the shoe bottom, spring means for pressing the leveling tool upon the bottom of the shoe, a toggle, mechanism operative upon straightening said toggle for lifting the tool against the action of said spring means, a spring urging said toggle into straightened position, latch means holding said toggle in broken position with the shoe support in its forwardmost position in which a shoe carried thereon is located forwardly of the leveling tool, means operative in response to initial rearward movement of said shoe support for releasing said latch means, and means operative in response to further rearward movement of the shoe support to carry the shoe beneath the leveling tool for rendering said mechanism ineffective whereupon the tool is held by the spring means against the shoe bottom during the leveling operation.

50

4. In a leveling machine, a shoe support, a leveling tool, means mounting said shoe support for movement in directions lengthwise of a shoe thereon to cause the leveling tool to operate progressively along the shoe bottom, spring means for pressing the leveling tool upon the bottom of a shoe, a toggle, mechanism operative upon straightening said toggle for lifting the tool against the action of said spring means, a spring urging said toggle into straightened position, latch means holding said toggle in broken position with the shoe support in its forwardmost position, a rod movable forwardly and rearwardly of said machine, means pivotally mounting said latch means on said rod, means urging said rod forwardly of the machine, means carried by said shoe support for holding said rod in a rearward position with the shoe support in its forward position, and means operative upon initial forward movement of said rod from its rearward position for releasing said latch means.
5. In a leveling machine, a shoe support, a leveling tool, means mounting said shoe support for movement in directions lengthwise of a shoe thereon to cause the leveling tool to operate progressively along the shoe bottom, spring means for pressing the leveling tool upon the bottom of a shoe, a toggle, mechanism operative upon straightening said toggle for lifting the tool against the action of said spring means, a spring urging said toggle into straightened position, latch means holding said toggle in broken position with the shoe support in its forwardmost position, a rod movable forwardly and rearwardly of said machine, means pivotally mounting said latch means on said rod, means urging said rod forwardly of the machine, means carried by said shoe support for holding said rod in a rearward position with the shoe support in its forward position, and means operative upon initial forward movement of said rod from its rearward position for releasing said latch means.
